BINDER

Robert R. Webb, Los Angeles, Calif., assignor to
 Charles R. Hadley Company, Los Angeles,
 Calif., a corporation of California

Application January 27, 1933, Serial No. 653,779

3 Claims. (Cl. 129—13)

This invention relates to adjustable loose-leaf binders in which the loose leaves are clamped between two cover members joined by posts or pillars extending through apertures provided therefor in the loose leaves.

An object of the invention is to provide a reliable binder that is inexpensive to manufacture, is simple to handle and is positive in operation.

Another object is to provide a binder having a gravity operated locking mechanism that functions in a positive manner and yet permits varying the opening between the cover members by very small increments.

Other objects and features of the invention will be apparent from the following detailed description which refers to the drawing.

In the drawing:

Figure 1 is a perspective view of a portion of a binder in accordance with my invention.

Figure 2 is a sectional view taken in a plane through the posts of the binder.

Figure 3 is a detail sectional view through one of the clamping plates taken in the plane III—III of Figure 2.

Figure 4 is a detail sectional view showing the interlocking members of one of the locking posts of the binder, and

Figure 5 is a detail cross-sectional view through one of the locking posts taken in the plane V—V of Figure 4.

Referring to Figure 1, my binder comprises a pair of clamping plates designated generally at 1 for clamping the ends of loose leaves 2, with heavy cover leaves 3 hinged to the clamping plates 1 by hinges designated generally at 4.

Referring for the moment to Figure 3, each clamping plate 1 comprises a sheet metal element 5 bent into L-shape as shown, the long leg 6 of the L extending inwardly and forming a base plate to protect the rear edges of the loose leaves 2. The long legs 6 of the elements 5 on opposite sides of the binder overlap as shown in Figure 1. The short legs 7 of the L-shaped elements 5 constitute the faces juxtaposed to the loose leaves for compressing the latter. The free edge 7^a of each short leg 7 is slit adjacent each end and the portions beyond the slit curled as shown at 8 in Figure 1 to engage a cover hinge pin 9. The portion of the edge 7^a of each leg 7 between the slits is folded back to engage the outer surface of an outer cover plate 10 (Figure 3). The outer cover plate 10 has each end turned inwardly to contact with the outer face of the short leg 7 of the element 5 and thereby form an enclosure for

a post anchoring bar 11. It will be observed from Figure 3 that the front edge of the outer plate 10 is curved inwardly to correspond with the curvature of the rearwardly bent edge 7^a of the element 5. The rear edge 12 of cover plate 10 is bent inwardly at right angles to the outer face of the short leg 7 and then parallel thereto to engage with the rear edge of the bar 11. The element 5, the cover plate 10 and the post anchoring bar 11 constituting each clamping plate 1 are firmly secured together by rivets 13 passing through apertures provided therefor in the various elements.

Referring now to Figure 2, the opposite clamping plates 1 are secured together for movement toward and away from each other by a plurality of telescoping posts secured to the post anchoring bars 11. Two types of posts are preferably used, the outer posts 14 in Figure 2, each containing a spiral spring 15 therewithin for normally forcing the two clamping plates 1 apart and the two inner posts 16 comprising a locking mechanism for preventing, under certain conditions, relative outward movement of the clamping plates 1.

Each pair of posts 14 comprises an outer post 17 and an inner post 18, one end of post 17 being anchored to one of the bars 11 and the opposite end of post 18 being anchored to the opposite bar 11. These posts are preferably secured in their respective anchoring bars by forcing them through apertures in the bars slightly smaller than the outer diameters of the posts and flaring the inner ends of the posts outwardly to prevent their withdrawal from the bars. The outer posts 17 are provided with plugs 19 at their inner ends to constitute thrust plates for the springs 15. The opposite ends of the springs bear against similar thrust plates 20 adjacent the ends of the smaller tubes 18.

Each locking post assembly 16 comprises an outer hollow post 21 and an inner post 22 secured to the opposite anchoring bars 11. The outer posts 21 may be secured to the anchoring bar by forcing them into apertures in the bar 100 slightly smaller than the outside diameters of the posts and flaring the inner ends as described in connection with the posts 17 and 18. The inner posts 22 are preferably threaded into the opposite bar 11 to facilitate assembly of the 105 binder. The inner surface of each outer post 21 is provided with coarse screw threads substantially throughout its length as shown at 23, and is provided with a shoulder 24 at its outer end to prevent complete withdrawal of the inner 110

post 22 therefrom, the latter having an enlarged end 25 engageable with shoulder 24.

Referring now to Figure 4, the enlarged end 25 of each inner post 22 is dimensioned to slide 5 readily within the threaded portion of the outer post 21, and is provided with three recesses 26 symmetrically positioned about the post as shown in Figure 5. Each recess 26 is preferably formed by drilling into the enlarged end 25 at an angle. 10 Positioned in each recess 26 is a ball 27 of slightly smaller diameter than the diameter of the recesses so that it is free to move longitudinally in the recess. Each recess 26 is of sufficient depth to contain the ball 27 substantially within the 15 outer circumference of the enlarged portion 25 when the binder is positioned with the posts vertical and the enlarged ends 25 of posts 22 uppermost. Under these conditions the various balls 27 in the recesses 26 of the binder posts 20 all lie in the inner ends of the recesses out of contact with the threaded inner surfaces of the outer posts 21. There is therefore nothing to prevent separation of the opposite clamping plates 1 and the latter will be forced apart by 25 the springs 15 in the posts 14 until the enlarged heads 25 on the posts 22 engage with the shoulders 24 of the outer posts 21.

When it is desired to force the plates 1 together and retain them in clamping position 30 against loose leaves therebetween, the entire binder is inverted from the position last described so that the enlarged ends 25 of the posts 22 are lowermost. In this position the balls 27 are urged by gravity outwardly along the inclined 35 recesses 26 so that they lie against the threaded inner surfaces of the outer posts 21. If the uppermost clamping plate 1 is then forced downwardly, the posts 22 are moved downwardly within the posts 21 and the balls 27 move inwardly in their 40 recesses as they engage successive threads on the inner surface of the posts 21. The balls therefore offer no resistance to inward movement of the posts 22. However, when the cover plates have been moved sufficiently close together and 45 the pressure thereon is released, the cover plates tend to separate because of the pressure exerted by the springs 15 and by the loose leaves 2. This tends to cause the inner posts 22 to move outwardly within the posts 21. Such movement, 50 however, is immediately prevented because one or the other of the balls 27 will immediately wedge between the inner wall of its recess and a thread on the outer post 21. The clamping plates 1 are thereby locked firmly against outward movement and the binder may be moved 55 into any desired position.

When it is desired to release the binder the latter is turned into a position with the posts vertical and the enlarged ends 25 of the inner posts 60 22 uppermost, and the detent balls 27 released from engagement with the threads in the outer post 21 by compressing the plates 1 slightly together. This slight movement releases the balls 27 which were engaged with the threads in the 65 outer posts 21 permitting them to fall into the inner ends of the recesses where they can no longer engage with the threads in the outer post. The clamping plates 1 will then be forced apart by the springs 15 when the pressure is released. 70 The recesses 26 on each post 22 are similarly positioned longitudinally; in other words, corresponding portions of each recess lie in the same transverse plane. On the other hand, because of the pitch of the screw threads in the outer posts 75 21, the balls in different recesses 26 on any one

post will engage with the threads of the outer post in different longitudinal positions of each inner post 22 within the associated outer post 21. As a result the inner post will lock with the outer post in three different positions within a longitudinal distance measured by the pitch of the screw threads. In other words, the opening between the clamping plates 1 may be varied by increments only one-third as large as they would be if only a single recess and ball were provided in each inner post 22. Of course if it is desired to make a binder adjustable by finer increments, more than three recesses may be provided on each post. 80

Since the clamping plates 1 are constructed of pressed steel elements they would be liable to mar surfaces on which the binder is placed, were they permitted to contact with the surfaces. To prevent contact between the metal portions of the binder and a supporting surface, bearing members 28 of rubber or other suitable material are provided at each corner of the binder. These bearing members 28, as shown in Figures 1 and 2, fit between the outer ends of the short legs 7 of the elements 5 and the cover plates 10, projecting beyond the end and rear edges of the outer cover plates 10 as shown. The rear edges 12 of the outer cover plates 10 are cut away adjacent the ends to permit the bearing member 28 to project rearwardly past the surface defined 105 by the base plates 6. Each bearing member 28 is provided with a central turret-shaped projection 29 which extends through an aperture in the outer cover plate 10. Since each bearing member 28 projects outwardly in three directions from 110 the binder, they prevent contact between the metal parts of the binder and a flat supporting surface in whatever position the binder may be placed. Each bearing member 28 is secured to the adjacent short leg 7 of element 5 by a rivet 115 30 the head of which is counter-sunk below the outer surface of the turret shaped projection 29.

Loose leaf binders for any given size of loose leaf are made with various numbers of posts, and with posts of different length. My design facilitates the construction of binders of different types for the same size of loose leaf, since the same outer plates 10 may be used on all types, and different numbers of posts may be provided by merely changing the post assemblies comprising the post anchoring bars 11 and the posts 14 and 16. If different post assemblies differ only in the length of the posts, the same elements 5 may be used with all. If the post spacings are different, it will of course be necessary to change 120 the elements 5 or provide these elements with extra post apertures. 125

I claim:

1. In a loose leaf binder, a pair of leaf clamping plates, each formed of sheet metal bent to L- 135 shape, the long legs of the two plates overlapping to constitute the base of the binder, and the inner faces of the short legs constituting the leaf compressing faces of the binder, the free edge of each short leg being slit adjacent each end and the 140 portions beyond the slits being curled to engage cover hinge pins, outer plates having inturned edges fitting against the outer surfaces of said short legs of said plates, the edge of each short leg between said slits being folded back over 145 the adjacent inturned edge of the outer plate, a bar positioned between each clamping plate and its associated outer plate, cooperating telescoping posts anchored to said bars, each clamping plate having apertures for said posts to pass through, 150

and means for securing each outer plate to the associated clamping plate.

2. A binder construction as described in claim 1 in which each outer plate is apertured adjacent each end, the rear inturned edges are cut away at the ends and a bearing member of relatively soft material is inserted between the outer plate and the clamping plate at each end, each bearing member projecting beyond the ends of the associated outer and clamping plates rearwardly beyond the inturned edge of the cover plate, and having a raised portion in its outer face projecting through the aperture in the end of the cover plate and beyond the outer surface of the cover plate.

3. In a loose leaf binder, a pair of leaf clamping plates formed of sheet metal, outer plates

having inturned edges fitting against the outer surfaces of said leaf clamping plates to form recesses therebetween, post anchoring bars in said recesses, cooperating telescoping posts anchored to said bars, said clamping plates having apertures for said posts to pass through, means for securing each outer plate to its associated clamping plate and post anchoring bar, spaced apart portions of one edge of each clamping plate extending beyond the adjacent inturned edge of the associated outer plate and curled to engage a cover hinge pin, and the edge portions of each of said clamping plates between said spaced-apart portions being bent back over the adjacent in-turned edge of the associated outer plate.
